United States Patent Office

Des. 203,910

Patented Feb. 22, 1966

203,910

BURNER LINER

Ben B. Sachnoff and Myron M. Levin, both of 4315 N. Lincoln Ave., Lincolnwood, Ill.

Filed Nov. 18, 1964, Ser. No. 82,676

Term of patent 14 years

(Cl. D81—25)

We claim:

The ornamental design for a burner liner, as shown.
